Letters Patent

The Schedule referred to in these Letters Patent and making part of the same containing a description in the words of the said William Jones himself of his improvement in the manufacture of iron in the two processes of it called puddling and heating.

To all to whom these presents shall come.

Be it known that William Jones of Amonshaw in the County of Rockland and State of New York have invented and useful improvement in the manufacturing of iron in the two processes of it called puddling and heating and that the following is a full and exact description of the construction and operation of said improvement as invented by me.

The improvement consists of a store or heating apartment attached to and connected with a puddling furnace and heated with the same fire as the one by which the puddling furnace is heated.

The ground plan or foundation of the furnace is a rectangular parallelogram about 14 feet long by 7 feet broad and consists of a layer of stone & brick upon this the walls of the furnace consisting of brick work and corresponding in elevation from with the foundation are erected. The height of the wall on the right side is about seven feet and on the left side about 7 feet 3 ins. each being well secured with iron plates or binders.

The flue or chimney goes from the center of the furnace & is of the usual form. The flue being rather large than common. The furnace internally is divided into three compartments communicating with one another viz. the store coal or fuel apartment and the puddling apartment which are on the same level & the store or heating apartment which is over the puddling apartment. — Over the store coal and puddling apartment

is unworked up of brick, extending lengthwise from the right side to within about 9 inches of the wall on the left side thus leaving of that width on the left side.

The height of the roof on the right side from the floor of the stove-coal apartment is about 8 feet 4 inches and at its termination near the left side and at the mouth of the puddling apartment about 10 inches.

Through this roof is an aperture nearly over the centre of the puddling apartment about seven inches by four inches dimensions communicating with the heating apartment above it, through which the iron when properly heated is dropped into the puddling apartment which is of an elliptical form with a cast iron bottom or floor. The coal and iron in the stove-coal and puddling apartments are prevented from mixing by a row of bricks called the bridge of about a foot in height extending across and separating the two apartments. The flame from the stove-coal or fuel apartments which is on the right being is caused horizontally over the puddling apartment to the floor in the left wing) before entering this which it passes to the heating apartment it then horizontally across the heating apartment to the stack which is finally conveyed off. The process of operation is to charge the iron in heating apartment with pig iron or spiced metal blooms, bolts, bars or other iron castings about 6 inches in length by 3 inches diameter, which is heated into nearly a molten state and when so heated is caused through the aperture before mentioned onto the puddling apartment & there wrought into bars without the necessity of a fresh fire being put on.
